SAFETY BANK DOOR

David G. Earl, Long Beach, Calif.

Application November 15, 1930, Serial No. 495,895

7 Claims. (Cl. 20—1.01)

This invention relates to a safety bank door through which employees enter the bank when coming to work in the morning, and before customers arrive.

5 An object of my invention is to provide a bank door for employees in which there is room for only one person at a time, thus precluding the possibility of a robber entering the bank with the employee.

10 Another object is to provide a bank door which can only be opened on a code signal to some point remote from the bank.

Still another object is to provide a door which is simple and sturdy in construction so that it 15 cannot be readily broken through.

Other objects, advantages, and features of invention may appear from the accompanying drawing, the subjoined detailed description, and the appended claims.

20 In the drawing:

Figure 1 is a perspective view of my door.

Figure 2 is a fragmentary, longitudinal, sectional view of the inner door locking arrangement.

Figure 3 is a fragmentary, perspective view 25 of the door ratchet and telephone.

Figure 4 is a fragmentary, transverse, sectional view of one corner of the door.

Referring more particularly to the drawing, my bank door comprises a pair of panels 1—2 30 which are positioned ninety degrees to each other, and these panels are secured to a vertical post 3 by means of which said panels are pivotally mounted. The post 3 is suitably journaled in a frame built into the building, and is very substantial. The panel 1 is on the outside of the building and is normally locked with any well-known type of lock.

A pair of inner panels 4—5 form the closure to the inside of the building and these panels 40 are mounted on a vertical shaft 6 which shaft is journaled in the frame of the building in the same manner as the post 3. As previously stated, the panels 1—2 are latched by an ordinary lock accessible from the outside, but the 45 inner panels 4—5 are latched by a mechanism controllable from a point remote from the bank.

The panels 1—2—4—5 form a rectangular vestibule or entryway which is just large enough 50 for one man to stand in. As will be subsequently described, two people could not enter into the vestibule and close the doors as required. The panels 1—2 swing together as do also the panels 4—5, and these panels swing in the direction of the arrows shown in Figure 1.

55 A ceiling (not shown) covers the entryway and

a floor 7 is provided at the bottom. The post 3 extends through the floor 7 into a compartment 8. An arm 9 is secured to the post 3 within the compartment 8. A dog 10 is pivotally mounted on the end of the arm 9, and this dog co-operates with ratchets 11 to hold the panels 1—2 against opening once said panels have been closed.

A shaft 12 extends into the compartment 8 from the inside of the bank and is provided 65 with a handle 13 to rotate the same. Pins 14 on the shaft are adapted to engage the dog 10 to swing the same on its pivot. Before leaving the bank at night, the dog 10 is swung back on its pivot so that it will drag over the ratchet 11. 70

Thus the employees coming to the bank in the morning unlock the panel 1, swings the panel outwardly and enters the vestibule or entryway. In order to enter, it is necessary that the panels 1—2 be returned to their closed position as shown 75 in Figure 1, and in doing so the ratchet is returned to the position shown in Figure 3 and the panel 1 cannot be again opened to permit the employee to pass out of the entryway.

The only way in which he can be released is to 80 give the code, as will be subsequently described, and enter the bank, or a fellow employee on the inside of the bank can swing the dog out of operative position and allow him to thus open the panel 1. However, with no one in the bank there 85 is only one exit from the entryway, and that is into the bank.

A telephone conduit 15 is positioned in the compartment 8 and extends along the arm 9 to a switch 16. When the panels 1—2 are in closed 90 position, i. e., as in Figure 1, the switch is closed and the telephone 17 may be operated. The telephone 17 is on the inside of the bank and is not accessible from the entryway except that a person may talk into the same. A receiver hook 95 18 extends through the wall of the entryway and is lifted when it is desired to talk into the telephone 17. A hole 19 extends to the telephone to permit the occupant of the entryway to speak into the telephone.

Once a man has entered as previously stated, he lifts the receiver hook 18 and calls a code number, sentence, or the like into the telephone. The telephone extends to the police station, or the like, and after the code has been heard, the telephone 17 is rung. This causes the lock shaft 20 to be released and swings the latches 21—21 out of engagement with catches 22—22 which are secured to, or may be an integral part of the panel 4. Thus when the telephone 17 is rung back, the 100 105 110

panels 4—5 are released and the person may enter the bank.

The panels 1—2—4—5 are so arranged that neither pair can be operated unless the other pair 5 is closed. Thus a person cannot partly open the panels 1—2 and attempt to get into the entryway allowing an exit for himself and hope to operate the panels 4—5. In the first place the telephone 17 is not connected unless the panels 10 1—2 are closed, and even if a connection could be made to the telephone, the panels 4—5 would not swing unless the panels 1—2 were closed. The telephone 17 is mounted on one of the stationary frame members or posts 23, and may be 15 suitably protected against tampering.

The panels 1—2—4—5 fit into stationary corner posts 23—24 so as to limit the inward swing of the panels. This arrangement is shown in Figures 3 and 4. Also to prevent unauthorized 20 tampering with the telephone 17, a carborundum plate 25 may be placed between the telephone and the post 23.

Having described my invention, I claim:

1. A safety bank door adapted to be mounted 25 in an opening to a bank, comprising two pairs of panels, each pair of panels being arranged at substantially 90 degrees, means pivotally mounting each pair of panels, said pairs of panels being so adapted and arranged to form a substantially rect- 30 angular enclosure, lock means for the inner pair of panels, said lock means being controllable from a remote point whereby admission is gained into the bank.

2. A safety bank door adapted to be mounted 35 in an opening to a bank, comprising an outer pair of panels and an inner pair of panels, both of said pairs being arranged at substantially right angles to each other, means pivotally mounting each pair of panels, said panels being so adapted 40 and arranged that a substantially rectangular enclosure is formed, ratchet means holding the outer pair of panels in closed position, lock means on the inner pair of panels and means to release said lock means from a remote point whereby ad- 45 mission is gained into the bank.

3. A safety bank door comprising an outer pair of panels and an inner pair of panels forming a closure, both of said pairs being arranged at substantially right angles to each other, means pivotally mounting each pair of panels, ratchet means holding the outer pair of panels in closed position, a telephone system, one telephone being within the closure, lock means on the inner pair of panels, operative means extending from the telephone within the closure to said lock means 55 whereby said lock means is released when the telephone is rung, from a remote point.

4. A safety bank door comprising an outer pair 60

of panels and an inner pair of panels forming a closure, both of said pairs being arranged at substantially right angles to each other, means pivotally mounting each pair of panels, ratchet means holding the outer pair of panels in closed position, a telephone system, one telephone being within the closure, lock means on the inner pair of panels, operative means extending from the telephone within the closure to said lock means whereby said lock means is released when the telephone is rung from a remote point, switch means on the outer pair of panels, said switch means controlling the telephone whereby said telephone is only operative when the outer pair of panels is closed.

5. A safety bank door comprising an outer pair of panels and an inner pair of panels, said panels co-operating to form an entryway, means pivotally mounting each pair of panels, a ratchet arm secured to the outer pair of panels, a dog pivotally mounted on the ratchet arm, a ratchet engageable by the dog whereby said outer pair of panels is held against movement, release means extending to said dog from the inside, a telephone system, one telephone being within the entryway, lock means for the inner pair of panels, and releasing means extending from the telephone to said lock means whereby said lock means is operated when the telephone is rung, from a remote point.

6. A safety bank door comprising an outer pair of panels and an inner pair of panels, said panels co-operating to form an entryway, means pivotally mounting each pair of panels, a ratchet arm secured to the outer pair of panels, a dog pivotally mounted on the ratchet arm, a ratchet engageable by the dog whereby said outer pair of panels is held against movement, release means extending to said dog from the inside, a telephone system, one telephone being within the entryway, lock means for the inner pair of panels, and releasing means extending from the telephone to said lock means whereby said lock means is operated when the telephone is rung from a remote point, and telephone switch 110 means on said outer pair of panels whereby said telephone is operative only when said outer pair of panels is closed.

7. A safety bank door adapted to be mounted in an opening to a bank, comprising two pairs of 125 panels, each pair being arranged at substantially 90 degrees, means pivotally mounting each pair of panels, said panels being so mounted and arranged as to form an enclosure, the enclosure being large enough for only one person to stand 130 within, lock means for the inner pair of panels, said lock means being controllable from a remote point.
